UNITED STATES PATENT OFFICE.

WILLIAM D. EWART, OF CHICAGO, ILLINOIS.

BUCKLE.

SPECIFICATION forming part of Letters Patent No. 237,506, dated February 8, 1881.

Application filed November 17, 1880. (No model.)

To all whom it may concern:

Be it known that I, WILLIAM DANA EWART, of Chicago, in the county of Cook and State of Illinois, have invented certain new and useful Improvements in Buckles; and I do hereby declare that the following is a full and exact description thereof, reference being had to the accompanying drawings, making part of this application.

10 My invention relates to certain new and useful improvements in buckles, the nature of which will be presently more explicitly described.

Under the older modes of construction of 15 buckles the frames were so made and the tongues so combined with them that the root of the tongue was not effectually held in a central position endwise of the back bar of the frame; but in the later modes of manufacture 20 the retention of the root of the tongue in a position about central (endwise) of the back bar of the frame (on which bar the tongue is hung) has been effected by placing the eye or loop formed at the root end of the tongue between 25 slight projections formed on the said back bar at the back side of the frame. In this construction of buckle, however, although the eye or loop of the tongue-root (which is bent round and hinges on the back bar of the frame) is held in place end- 30 wise of the bar on which it is hung, the point or free end of the tongue has considerable play laterally, so that it sometimes gets turned out of place and toward one of the front angles of the frame. This defect arises from the practical difficulty in (if not an impossibility of) 35 making the bent loop at the root of the tongue fit round the middle part of the back bar of the buckle with that perfection of bearing-surface which would be necessary to render the 40 tongue capable of free movement about said back bar as an axis of vibration, and yet incapable of any lateral vibration or swing.

One object of my invention is to cure this defect in buckles as heretofore made; and to 45 this end and object the first part of my invention consists in a buckle the back bar of the frame of which is made with a doubly-shouldered bearing at or near its middle portion, and adapted to fit in the eye of and confine 50 laterally at its root end the tongue of the buckle, and thus, while permitting the tongue

to vibrate freely about the back bar in the proper direction, confining it against any lateral movement, all as will be hereinafter more fully set forth.

55 Another imperfection sought to be cured by my invention is the defective fitting together of the back bar of the frame and the eye of the tongue that necessarily follows the usual method of articulating or hinging together 60 these parts—viz., by bending and shaping the material of the tongue at its eye around the back bar of the frame; and to remedy this defect is the object of the second part of my invention, which, to this end, consists in molding or casting the back bar of the frame within the cylindricaleye of the (previously-formed) tongue, whereby I am enabled to effect a perfect articulation about the back bar of an eye 65 (at the root of the tongue) which has the continuity of its bearing-surface unbroken, all as will be hereinafter more fully explained.

70 As heretofore made, the buckle-frame (when made of cast metal) has had a small depression or recess cast in the upper surface and at the 75 inner edge of the front bar, to receive and hold in place the lower part of the point of the tongue; but as in the manufacture the shapes of the points of the tongues, especially when made of cast metal, will vary some, and as it is desirable 80 to have always a perfect fit of the tongue's point in the recess of the front bar of the frame, I propose to render the manufactured article more desirable by having the recess to always 85 perfectly match the point of the tongue to be received in it; and to this end and object the third part of my invention consists in a buckle the recess in the front bar of the frame of which is formed by casting or molding said bar against the front end of the tongue, the 90 point of the latter thus serving as the pattern for the said recess, all as will be hereinafter more fully explained.

To enable those skilled in the art to which 95 my invention relates to make and use the same, I will now proceed to more fully describe the several features of the same, referring by letters to the accompanying drawings, forming part of this specification, and in which—

100 Figure 1 is a top view of a buckle made according to my invention. Fig. 2 is a similar

view, but with the point of the tongue broken off, (to better show the recess adapted to receive it,) and with the root portion of the tongue drawn in section, to better show the 5 shouldered bearing for the eye of the tongue. Fig. 3 is a side or edge view; and Fig. 4 is a section at $x x$, Fig. 1, but with the point of the tongue raised up, while Fig. 5 is a view of the tongue only of the buckle.

10 At Fig. 6 I have shown, in top view, (with the tongue turned back,) a modification of the buckle, in which the front bar is encircled by the usual roller, and consequently is not recessed at all, (for the accommodation of the 15 point of the tongue.)

In the several figures the same parts will be found designated by the same letters of reference.

10 In the buckle shown at Figs. 1 to 5, inclusive, every part is made of cast metal, preferably malleable iron, while the buckle seen at Fig. 6 is similarly made, except as to the tubular roller of the front bar, which, as usual, is made of sheet metal simply bent into cylindrical form to completely surround and loosely fit on the said bar.

The frame A of the buckle and its tongue B may be made of any design and size desired, and the former, when the buckle embraces all 30 the parts of my invention, is made, as shown, with a recess or depression at e , which is designed to accommodate the point d of the tongue. This tongue B is cast with an eye, e , at its attached end, the interior of which eye 35 e is perfectly cylindrical in form, and fits or conforms perfectly (though not tightly) to the central cylindrical portion, f , of the back bar of the frame, that lies between the two circular collars $i i$, formed on said back bar.

40 The collars $i i$ are preferably cast solid with the back bar of the frame A, and the cylindrical part f of said bar lying between said collars is made of about the same diameter, and consequently of about the same strength 45 and durability, as if the said back bar were of the old-fashioned pattern, not provided with the means for holding the root of the tongue laterally. This is important, because, if the said back bar should be materially reduced at its 50 middle portion to form a shouldered bearing for the eye of the tongue's root, said bar would be weakened to an extent not compensated for by the advantage of holding the tongue properly in place; and in order to get shoulders sufficient for the designed purpose said back bar would have to be so reduced as to materially weaken it.

The eye e completely surrounds the journal-like part f of the frame, and is cast solid with 60 the rest of the tongue B, and without any break or joint in it. To make the buckle with this sort of eye e thus coupled with the back bar of the frame A, I first cast the tongue B perfect, as seen at Fig. 5. I then place this 65 tongue properly in the mold in which the frame A is to be cast in such manner that in pouring the metal for the frame-casting it will run

through and fill the bore of the eye e , and also flow (in the mold) around the lower part of the point d of the tongue, the collars at $i i$ being formed, of course, at the same time, by the mold in which the frame is cast. By preference I thus mold the frame round about the tongue before having cleaned the casting B, because the sand usually left on the surface 75 of the tongue-casting may tend to make the part f cast very slightly smaller than it otherwise might, and thus the subsequent separation of the surface of f from the bore-surface of eye e may be facilitated; but the natural shrinkage of 80 the metal of frame A in cooling will insure a ready separation of the adjacent surfaces of eye e and bar f , so that after the article shall have been finished (by the usual malleableizing and cleaning processes) the tongue B may be 85 easily turned on its pivotal bar at f , and will always after work thereon with perfect freedom, though without any side motion or wobble to the tongue, since the eye e will always fit perfectly on the part f and between the 90 right-angular shoulders formed at the ends of portions f by the collars $i i$.

If deemed expedient, the pattern or shape of the eye may be so varied at each side or end, and that of the collars $i i$ may be so 95 changed, that in the described process of manufacture these collars $i i$ will set slightly within correspondingly-shaped depressions in the end portions of the eye e ; but such and other mere modifications are, of course, not material 100 to the described invention.

So far as the first part of my invention is concerned, the buckle might be made without either casting the back bar through the solid eye e or using any depression at e for the point 105 of the tongue, because the latter feature of construction may, as illustrated in the kind of buckle seen at Fig. 6, be omitted without depriving the article of the advantages consequent to the use of either the first or the second features of my invention, and because by 110 making the eye e open or U-shaped in casting the tongue B (as illustrated by the dotted lines at Fig. 1) said eye might be subsequently bent around the part f and into precisely the shape 115 already described, thus producing substantially the same construction, though in a more expensive and laborious manner and with less perfection of manufacture.

By using the point d of the tongue as the 120 pattern for molding in the recess e it follows, of course, that every buckle of any number manufactured will have the point d and recess e matching together better than if the recess e were molded by another pattern to which all 125 the cast tongue-points might not, by reason of variations in said tongue-castings, exactly fit.

I need not describe any more minutely than I already have the process of casting the back bar of the frame through the previously-cast 130 eye portion e of the tongue, as this process, *per se*, is analogous to that practiced in the casting of one part onto another, so as to be capable subsequently of motion between the

connected parts in the manufacture of other articles, and is understood by those skilled in the arts and familiar with the manufacture of articles in which such process is employed.

5 As I have already clearly indicated, separate parts only of my invention may be used with more or less advantage, though I prefer to always employ together both the first and second parts, and to always use also, where 10 the buckle is not of such character as to render it inapplicable, (as indicated, for instance, at Fig. 6,) the third part of my invention.

Having now so fully explained the nature 15 of the several features of my invention and so described each as to its construction and operation that those skilled in the art can make and use buckles embodying either one or more of said features of invention, what I claim as new, and desire to secure by Letters 20 Patent, is—

1. A buckle the back bar of the frame of which has collars *i i*, forming raised shoulders

adapted to retain the root of the tongue laterally, and which has a tongue, the eye or loop of which encircles that portion of the back 25 bar lying between said shoulders, all substantially as and for the purpose set forth.

2. A buckle having the back bar of the frame provided with raised shoulders and a tongue, the eye at the root of which fits around 30 the back bar, and between its shoulders, and is cast solid, substantially as set forth.

3. As an improved method of manufacture of buckles having cast frames, molding the recess for the tongue-point of each buckle by 35 the point of its tongue-piece, as and for the purpose set forth.

In witness whereof I have hereunto set my hand this 13th day of November, 1880.

WILLIAM D. EWART.
